United States Patent Office.

H. SLOAT, OF WATERTOWN, NEW YORK.

Letters Patent No. 96,156, dated October 26, 1869.

IMPROVEMENT IN SAW-SETS.

The Schedule referred to in these Letters Patent and making part of the same.

To all whom it may concern:

Be it known that I, H. SLOAT, of Watertown, in the county of Jefferson, and State of New York, have invented a new and useful Improvement in Saw-Sets; and I do hereby declare that the following is a full, clear, and exact description thereof, which will enable those skilled in the art to make and use the same, reference being had to the accompanying drawing, forming part of this specification.

The drawing represents a side view, partly in section, of my improved saw-set.

This invention relates to a new implement for setting all kinds of saws. It can be applied without removing the saw from the mandrel, and will set the teeth very accurately and evenly.

The invention consists in the general arrangement of cam-levers, fixed and movable jaws, sliding punch, and gauge-piece, all combined as hereinafter more fully described.

A, in the drawing, represents the handle of my improved saw-set.

The handle is fastened to the lower end of a shank, or bar, B, which carries near its upper end a head, C, that projects from both sides of the shank, as shown.

To the upper end of the shank B is pivoted, by a pin, a, a lever D, projecting, also, from both sides, as shown.

E is a movable jaw, arranged to slide on the shank B, under the head, or fixed jaw C.

It is adjusted by a screw, b, and nut c, or by other equivalent means similar to the manner of working the jaw of a monkey-wrench.

The jaw E is notched on its upper face.

F is a punch, held by a spring, G, on the head C,

and fitting through an aperture of said head, as shown.

The spring tends to hold it up against the lever D. Its lower end is above the notch on the jaw E.

H is a lever, pivoted to that end of the jaw C through which the punch is not fitted. This lever has a cam-shaped upper end, working under the lever D. By moving the lower end of the lever H toward the handle, the cam will raise the contiguous end of the lever D, thereby forcing down the punch.

A saw-tooth placed over the notch of the jaw E will thereby be set.

For different kinds of saws, different notched jaws should be used. To avoid this, I provide plates I I, of different kinds, adapted to the various styles of saw-teeth, and place one of the same upon the jaw E, as shown, so that the saw will be set on such plate I.

The degree of set is regulated by a set-screw, d, fitted through the lever H, or shank, to arrest the lever at a suitable distance from the shank.

Having thus described my invention,

What I claim as new, and desire to secure by Letters Patent, is—

1. A saw-set, consisting of the shank B, fixed jaw C, movable jaw E, levers D H, and punch F, all combined and operating substantially as herein shown and described.

2. The notched plates I, arranged in combination with the movable jaws E and punch F of a saw-set, substantially as herein shown and described.

H. SLOAT.
